UNITED STATES PATENT OFFICE.

BERNARD BENEDICT, OF NEW YORK, N. Y., ASSIGNOR TO BEACON MINIATURE ELECTRIC CO., INC., OF NEW YORK, N. Y., A CORPORATION OF NEW YORK.

PORTABLE ELECTRIC LIGHT.

1,167,878.

Specification of Letters Patent. Patented Jan. 11, 1916.

Application filed February 12, 1915. Serial No. 7,692.

To all whom it may concern:

Be it known that I, BERNARD BENEDICT, a citizen of the United States, and a resident of the Bronx, New York, in the county 5 of Bronx and State of New York, have invented certain new and useful Improvements in Portable Electric Lights, of which the following is a specification.

The invention pertains more particularly 10 to the class of portable electric lights commonly called lanterns, the exterior shell or casing of the article being provided with a suitable handle or suitable handles whereby the lantern may be conveniently carried.

15 The object of the invention is to produce a portable lantern light which may be conveniently manufactured and carried and which shall be reliable in use.

The exterior shell or casing of the light 20 will preferably be formed of metal and comprises a body portion to which the handle or handles will be secured and a hinged upper end portion serving as a cap and carrying the lamp, circuit closer switch and 25 suitable conductors, one leading to the lamp and the other to the positive pole of the battery.

The portable light of the present invention is adapted for use in connection with 30 an ordinary No. 6 dry cell, the latter being at its sides and bottom inclosed by the usual pasteboard carton which insulates said portions of the battery from the exterior casing.

The invention resides in the novel construction and combination of parts herein-after described and particularly pointed out in the claims, and said invention will be understood from the detailed description hereinafter presented, reference being had to the 40 accompanying drawings, in which:

Figure 1 is a perspective view of a portable electric light embodying the invention; Fig. 2 is a central vertical section, partly broken away, through the same, said section 45 being taken on the dotted line 2-2 of Fig. 3; and Fig. 3 is a transverse section through the same taken on the dotted line 3-3 of Fig. 2.

In the drawings, 10 designates the exterior 50 tubular shell or casing of the light, said shell preferably comprising a body portion 11 and a hinged cover portion 12. Upon the body portion 11 I by preference secure a rigid handle 13 and a hinged handle or 55 bail 14.

15 designates the hinge by which the cover portion 12 is secured to the body portion 11 of the general casing, and this hinge may be utilized as a means for placing the body portion 11 in electrical connection with 60 the cover portion 12.

Within the body portion 11 may be inserted, from the upper end thereof, a standard No. 6 dry cell 16 or other suitable battery and preferably the battery will about 65 fill said body portion 11. The battery will have upon it an ordinary carton 17 which will serve to insulate the bottom and sides of the zinc pole of the battery from the exterior metal casing.

At the upper edge of the rear side of the body 11 I preferably secure by hinging, as at 18, a metal conducting plate shown in this instance as being of right-angle formation and composed of members 19, 20, the member 20 being adapted to extend upwardly into and bear against the inner surface of the cover 12, and the member 19 being bifurcated and adapted to straddle a binding post or screw 21 upon which is placed a nut 22 70 serving to bind said member 19 downwardly against a metal washer 23 connected with the zinc pole of the battery. The members 19, 20 serve as efficient means for electrically connecting the cover 12 with the zinc 75 pole of the battery, but it is to be understood that I do not limit my invention to the employment of the member 20 since with the member 19 hinged to the body 11, and the body 11 secured by a hinge to the cover 80 12, there will be an electrical connection, without the member 20, between the zinc pole of the battery and the cover 12.

I prefer, however, to employ the member 20 because when the cover 12 is closed upon the body 11 said cover will engage the member 20 with a firmness which will at all times insure a reliable electrical connection of the zinc pole of the battery with the cover.

Within the top of the cover 12 are three 100 layers of fiber or other insulating material 24, 25 and 26, respectively, these layers being in face to face contact and riveted together and to the top of the cover. The upper layer or disk 24 is formed with a segmental 105 slot 27 coinciding with a corresponding slot 28 formed in the top of the cover 12. Within the layer or disk 25 is formed a segmental opening 29, and upon the layer or disk 26 is secured a switch arm 30, which has a stem 110

- 31 projected upwardly through the segmental slot 27 in the layer 24 and the slot 28 in the top of the cover 12. The arm 30 is pivotally secured at one end by a screw 32, 5 and this screw extends downwardly through the lower layer or disk 26 and receives one metallic end of a conductor 33, a nut serving to bind said metallic end of the conductor upon the screw 32, as shown in Fig. 2. 10 The other end of the conductor 33 is connected with one terminal of the lamp 34. In the recess 29 of the disk or layer 25 is an exposed head of a screw 35, said screw extending downwardly through the layer or 15 disk 26 and having connected with it the metal terminal at one end of the conductor 36, a nut, as shown in Fig. 2, serving to bind said terminal upon said screw 35. The other end of the conductor 36 is connected- 20 by a screw 37 and nut 38 with the carbon pole of the battery. When the switch arm 30 is away from the screw 35 or in the position shown in Fig. 3, the circuit will be open, there then being no electrical connection 25 between the conductors 33, 36, but when by means of the exposed pin 31 the arm 30 is turned on the screw 32 until its outer end is upon the screw 35, the circuit will be closed, since at that time the switch arm will serve 30 as a conductor connecting the screws 32, 35 of the conductors 33, 36. The threaded lamp socket is screwed within a threaded sleeve 39 of a reflector 40, and said sleeve is screwed within a semi-spherical shell 41, 35 which is fastened to the cover 12 and not only receives the reflector and lamp bulb, but also, at its outer end, a lens 42 which is held in place by a suitably threaded ring 43. One terminal of the lamp is in electrical 40 connection with the conductor 33 and the other terminal of the lamp is in electrical connection with the cover 12, which, as has been explained, is electrically connected with the zinc pole of the battery. When the 45 switch arm 30 is turned to connect the screws 32, 35 and thereby the conductors 33, 36, the circuit is from the carbon pole of the battery through the conductor 36, switch arm 30 and conductor 33 to one terminal of the lamp, and thence from the other terminal of the lamp through the metal cover 12 and conducting members 20, 19 to the zinc pole of the battery. The circuit may be completed, therefore, simply 50 by turning the switch arm 30 to connect the screws 32, 35 and broken by reversing the movement of the switch arm when restoring it to its normal inoperative position shown in Fig. 3. 55
- 60 The lamp of my invention is comparatively inexpensive of manufacture and reliable in operation and adapted to receive dry cells of commercial character, the battery being retained in the body portion 11 65 of the exterior casing and held against slid-

ing movement by the plate 19 projecting laterally over the same from the upper edge of said body and held down upon the battery by the nut 22.

What I claim as my invention and desire 70 to secure by Letters Patent, is:

1. In a portable electric light an exterior casing having a body-portion and a cover-portion carrying the lamp, one terminal of which is in electrical connection with said cover-portion, a battery within said body-portion and normally out of circuit and having exposed pole contacts, means electrically connecting the negative pole contact of the battery with said cover-portion, contact parts carried by and insulated from said cover-portion and from each other and respectively electrically connected with the other terminal of the lamp and the carbon pole of the battery, and a circuit closer carried by said cover-portion and manually operable to connect said contact parts, for completing the circuit, said cover-portion being hinged to said body-portion and said body-portion having a hinged plate to engage the negative pole contact of the battery. 85

2. In a portable electric light an exterior casing having a body-portion and a cover-portion carrying the lamp, one terminal of which is in electrical connection with said cover-portion, a battery within said body-portion and normally out of circuit and having exposed pole contacts, means electrically connecting the negative pole contact of the battery with said cover-portion, contact parts carried by and insulated from said cover-portion and from each other and respectively electrically connected with the other terminal of the lamp and the carbon pole of the battery, and a circuit closer carried by said cover-portion and manually operable to connect said contact parts, for completing the circuit, said cover-portion being hinged to said body-portion and said body-portion having a hinged plate to engage the negative pole contact of the battery. 90

100

3. In a portable electric light an exterior casing having a body-portion and a cover-portion carrying the lamp, one terminal of which is in electrical connection with said cover-portion, a battery within said body-portion and normally out of circuit and having exposed pole contacts, means electrically connecting the negative pole contact of the battery with said cover-portion, contact parts carried by and insulated from said cover-portion and from each other and respectively electrically connected with the other terminal of the lamp and the carbon pole of the battery, and a circuit closer carried by said cover-portion and manually operable to connect said contact parts, for completing the circuit, said cover-portion being hinged to said body-portion and said body-portion having a hinged right-angular plate one member of which is engaged with the negative pole contact of the battery and the other member of which is engaged with said cover-portion. 110

130

pleting the circuit, the means insulating said contact parts from said cover-portion comprising three layers of insulating material secured to one another and to the top of said cover-portion, the inner one of said layers having said contact parts secured to it, the next inner layer having a recess or opening therein housing the circuit-closer and the outer layer and the top of the cover being correspondingly slotted to expose a finger-piece on the circuit-closer.

4. In a portable electric light an exterior casing having a body-portion and a cover-portion carrying the lamp, one terminal of which is in electrical connection with said cover-portion, a battery within said body-portion and normally out of circuit and having exposed pole contacts, means electrically connecting the negative pole contact of the battery with said cover-portion, contact parts carried by and insulated from said cover-portion and from each other and respectively electrically connected with the other terminal of the lamp and the carbon pole of the battery, and a circuit closer carried by said cover-portion and manually operable to connect said contact parts, for completing the circuit, the means insulating said contact parts from said cover-portion comprising three layers of insulating material secured to one another and to the top of said cover-portion, the inner one of said layers having said contact parts secured to it, the next inner layer having a recess or opening therein housing the circuit-closer and the outer layer and the top of the cover being correspondingly slotted to expose a finger-piece on the circuit-closer.

closer being an arm pivotally connected with one of said contact parts and adapted to be turned to engage the other of said parts.

5. In a portable electric light an exterior casing having a body-portion and a cover-portion hinged thereto carrying the lamp, one terminal of which is in electrical connection with said cover-portion, a battery within said body-portion and normally out of circuit and having exposed pole contacts one of which is electrically connected with said cover-portion, contact parts carried by and insulated from said cover section and from each other, a conductor connecting one of said parts with the other terminal of the lamp, a conductor connecting the other of said parts with the other exposed pole contact of the battery, and a circuit closer carried by said cover-portion and manually operable to connect said contact parts, for completing the circuit, the means insulating said contact parts from said cover-portion comprising three layers of insulating material secured to one another and to the top of said cover-portion, the inner one of said layers having said contact parts secured to it, the next inner layer having a recess or opening therein housing the circuit-closer and the outer layer and the top of the cover being correspondingly slotted to expose a finger-piece on the circuit closer.

Signed at New York city, in the county of New York and State of New York, this 9th day of February, A. D. 1915.

BERNARD BENEDICT.
